UNITED STATES PATENT OFFICE.

WILLIAM F. REMPPIS, OF READING, PENNSYLVANIA.

DESIGN FOR A SPROCKET-WHEEL.

SPECIFICATION forming part of Design No. 31,535, dated September 19, 1899.

Application filed August 22, 1899. Serial No. 728,127. Term of patent 7 years.

To all whom it may concern:

Be it known that I, WILLIAM F. REMPPIS, a citizen of the United States of America, and a resident of Reading, in the county of Berks and State of Pennsylvania, have invented and produced a new and original Design for a Sprocket-Wheel, of which the following is a specification.

The drawing is a full-face view of a sprocket-wheel, showing my design.

The leading feature of my design consists of a double series of symmetrically-arranged openings in the wheel-plate between the central opening *c* and the toothed rim *d*, with intervening narrow bars, as shown in the drawing. The first series *a* of these openings are each of irregular oval shape, as indicated, the outer curve being formed of an inner arc of the rim *a'*, and the series *b*, located between

the inner concentric ring *e* and the intersecting strips or bars *f*, forming the inner boundary of the oval opening *a*, are of triangular form with curved lines, as shown, and are separated from each other by a series of connecting-strips *g* between the ring *e* and the reversely-curved bars *f*. Series of holes *h* and *i* are provided at the intersections of the several bars.

What I claim is—

The design for a sprocket-wheel substantially as shown and described.

Signed by me at Reading, Pennsylvania, this 19th day of August, 1899.

WILLIAM F. REMPPIS.
